(57) CLAIM

The ornamental design for a snow slider frame, as shown and described.

DESCRIPTION

FIG. 1 is a top, right, front isometric view of a snow slider frame embodying our new design;

FIG. 2 is a front view thereof;

FIG. 3 is a right side view thereof, the left side view being a mirror image thereof;

FIG. 4 is a top view thereof;

FIG. 5 is a bottom view thereof; and,

FIG. 6 is a rear view thereof.

The mid pole is shown fragmented in FIG. 1 to indicate indeterminate length.

The broken line showing is for illustrative purposes only and forms no part of the claimed design.
